PUMPING OF RUBBER LATEX AND THE LIKE AND APPARATUS THEREFOR

Application filed February 28, 1928, Serial No. 257,691, and in Great Britain March 2, 1927.

This invention relates to means for effecting the forced movement or pumping of liquid dispersions or emulsions which are liable to undergo flocculation or coagulation on being subjected to, for instance immoderate agitation or impact shock.

Liquid dispersions or emulsions contemplated as coming under consideration in this invention comprise the latices of rubber or other vegetable resins, artificial dispersions such as of rubber or of other vegetable resins or of coagulated rubber or of waste rubber or rubber reclaim or vulcanized dispersions of rubber or other vegetable resins, or artificial dispersions of synthetic resins or cellulose compounds or again mixtures of any of the aforesaid dispersions, any of which may or may not contain any one or more of the usual and known compounding ingredients.

According to the present invention the means utilized for effecting the forced movement or pumping of liquid dispersions of the aforesaid kinds and nature is a pump adapted to function by the deformation or reformation or similar displacement of a resilient member or chamber, it being preferable that the reformation of said member or chamber draws the dispersion from one vessel and that the deformation of the said member or chamber discharges the dispersion so drawn into another vessel or vice versa. In this manner the clogging of any interstices with coagulum from the dispersions is avoided.

The invention is applicable in a variety of instances necessitating the forced movement or pumping or circulation of dispersions, particularly latex. Thus it is especially suitable for use in the circulation of liquid dispersions through a container, such as is described in our application of even date, while it can equally well be utilized in the pumping of latex from transport tankers into storage vats in the factory.

Referring to latex, almost insuperable dif-

iculties attend the use of pumps having sliding parts, or bearings or glands, which contact with the latex. It is practically impossible to prevent the infiltration of the rubber globules between the stationary and the moving parts and consequent rapid coagulation of the latex adjacent those parts.

Thus the use of pumps of the usual reciprocating piston type is precluded in as much as if the coagulum formed adjacent the piston is allowed to remain, the pump rapidly becomes clogged and unable to function. To avoid the difficulties associated with this kind of pump, various other expedients have been resorted to. For instance rotary or turbine pumps have been utilized, but these as applied to the pumping of latex have been comparatively complicated and inefficient. Bearings or glands exposed to the latex rapidly become clogged with coagulum and special constructions have had to be devised in which the rotors are carried on bearings wholly clear of the latex. Air pumps have also been utilized for the movement of latex but known kinds of such pumps have only a very limited range of application and are not generally practicable.

The invention will now be described by way of example with reference to the accompanying drawings in which:

Figure 1 is a sectional side elevation of a pump constructed for use with rubber latex. Figure 2 is a plan view thereof, while Figures 3 and 4 show diagrammatically alternative arrangements.

Referring to Figures 1 and 2, the resilient member is in the form of a disc diaphragm 1 extending across an orifice 2 in a chamber or cavity 3 disposed between the inlet and outlet valves 4 and 5 respectively.

The said member is preferably actuated by a reciprocating rod 6 the operating mechanism for which includes a driven pulley 7, gearing 8, a crank shaft 9, a connecting rod 10, and a bell crank lever 11 fulcrumed at

12. That surface of the diaphragm 1 which contacts with the latex is removed from the surrounding surfaces. It has been found that if the diaphragm is allowed to contact or to approach closely the walls of the cavity 3 coagulation of the latex very rapidly results from the trapping thereof between said opposing surfaces.

13. A substantially analogous provision is made at the valves. As shown in the drawings, in ball valves the seating is reduced to a more or less sharp edge 13 removed as far as is convenient from the surrounding surfaces. Further in ball valves means are provided to prevent undue displacement of the ball thereof—both to ensure that the ball returns accurately to its seating and that it so returns almost immediately after cessation of discharge. As shown in the drawings, said means conveniently consists of a suitably arranged stop 14 limiting the vertical lift of the said ball.

14. In the alternative construction shown diagrammatically in Figure 3, the cavity 3 between the valves 4 and 5 is wholly inextensible and the resilient member is in the form of an envelope 15 distensible by inflation. To allow said envelope to collapse into a small compass, the same is preferably formed to assume 15—deflated—the cross sectional shape indicated at 16. The actuating fluid is alternately admitted and exhausted via a suitable valve 17—distention of the envelope causing displacement, through the outlet valve 5, of the latex around it in the cavity, and contraction of the said envelope drawing more latex into the said cavity through the inlet valve 4.

16. In general, however, it will be apparent that the resilient member may take any convenient form. Thus for example the said resilient member may be in the form of a bellows-like chamber preferably disposed between two substantially rigid end members adapted to move towards and away from each other.

17. In a further modification designed specifically to avoid the use of valves altogether, the resilient member is in the form of a tube and the actuating means are rollers travelling in such an orbit relative to the said tube that in sequence, they approach it, completely constrict it at one point, and then roll along its length to displace the latex so trapped. Two or more series of rollers are provided and their orbits are arranged to preclude back-flow of the latex.

18. Further while the description has been confined to valves such as ball valves adapted to be actuated by the displacement of the latex, it will be apparent that alternatively we may utilize positively actuated valves. For instance as illustrated diagrammatically in Figure 4 such valves may comprise distensible members 18 and 19 adapted to close the ori-fices into the chamber 3 of the inlet and outlet

19. pipes 4a and 5a respectively. The inflation of alternate envelopes and the actuation of the forcing diaphragm 20 would be timed so that on the suction stroke of the said diaphragm the envelope 19 would be distended to close the outlet pipe while on the discharge stroke the envelope 18 would be distended to close the inlet pipe. As shown in Figure 4 the diaphragm may be fluid actuated under the control of a distributing valve 21.

20. Finally it will be apparent that the features described in connection with one application of our invention may where applicable, with or without modification or addition, be utilized in connection with any of the other applications of the said invention.

21. What we claim is:

22. 1. Means for pumping aqueous dispersions which are coagulated by friction, comprising a pump body, a resilient diaphragm constituting one wall of the pump body, means engaging the diaphragm for repeatedly changing the internal volume of the pump body, and inlet and outlet valves comprising valve chambers, inflatable members within the valve chambers adapted to obstruct the fluid passage when inflated and leave a passage for the fluid when deflated, and means for successively inflating and deflating the said members in timed relationship with the changes in the internal volume of the pump body.

23. 2. A pump valve comprising a valve chamber, an inflatable member adapted to obstruct the fluid passage when inflated and leave a passage for the fluid when deflated, and means for periodically inflating and deflating the said member.

24. 3. A pump valve comprising a valve chamber, an inflatable sac adapted to fill the valve chamber when inflated and leave a passage for the fluid when deflated, and means for periodically inflating and deflating the sac.

25. 4. A pump comprising a chamber, fluid operated means for periodically drawing the fluid to be pumped into the chamber and forcing it out of the chamber, inlet and outlet valves comprising valve chambers, inflatable members within the valve chambers adapted to obstruct the fluid passage when inflated and leave a passage for the fluid when deflated, and conduits connecting the inflatable members with the fluid actuating the pump proper whereby the valves are opened and closed in synchronism with the operation of the pump proper.

26. 5. A pump comprising a pump body, a resilient diaphragm constituting one wall of the pump body, a hydraulic cylinder operatively connected to the diaphragm, means for introducing a liquid under pressure alternately into the two ends of the cylinder to reciprocate the said diaphragm, inlet and outlet valves comprising valve chambers, inflatable members within the valve chambers adapted

to obstruct the fluid passage when inflated and leave a passage for the fluid when deflated, and conduits connecting the respective inflatable members with the fluid in the two 5 ends of the cylinder whereby the valves are opened and closed in synchronism with the movements of the diaphragm.

In witness whereof, we have hereunto signed our names.

10 HARRY WILLSHAW.
